Des 906 —

S. M. Gibbs, of Albany, N. Y.

Assignor to

Rattitone & Co. of the same place.

Letters Patent No. 906. Dated July 7, 1857

The schedule referred to in these Letters Patent and making part of the same

Be it known, that I, Samuel M. Gibbs, of the City of Albany, and State of New York, have produced a new and original ornamental design, for the plates of a cooking stove, (which stove is called the Commonwealth) and I declare that the annexed delineations, are full and accurate representations of the said plates, which are combined to form in part the said stove, with their ornamental parts; the oven doors and the front doors, not represented in the separate views, being symmetrically similar to each other.

Des. 906

What I claim as my production and desire to secure by Letters Patent, is the combination and arrangement of ornamental figures and forms, represented in the accompanying drawings, forming together the ornamental design for the plates of a Cooking Stove.
